UNITED STATES PATENT OFFICE

FREDERICK C. LANDSITTEL, OF COLUMBUS, OHIO

BOOKHOLDER

Application filed October 22, 1931. Serial No. 570,408.

The present invention provides an improved adjustable holder adapted for the retention and support of relatively large and heavy books which, normally, are too bulky or 5 awkward to permit of their convenient manual handling, for example, reference books such as dictionaries, catalogs, directories, atlases, etc.

It is an outstanding object of the present 10 invention to provide a book holder of improved, simplified and efficient mechanical construction wherein a contained book will be securely retained by the holder in a closed position and wherein release mechanism is 15 provided, which must be positively operated before the holder and the book associated therewith may be opened.

It is another object of the invention to provide a holder which is of such construction 20 that the book received therein by virtue of its own weight, and by utilizing the force of gravity, operates to retain the book in the holder in a closed position.

It is another object of the invention to provide 25 a holder consisting of a book receiving frame formed to include a pair of spaced hingedly connected wings between which the book supported by the holder is retained and wherein the construction is such that upon 30 the operation of the aforesaid release mechanism, the wings may be swung outwardly to permit of the opening of the book.

It is a further object of the invention to provide 35 a book holder with a base and to pivotally mount the adjustable book supporting frame on the base so that said frame and a book contained thereby may be rotated about a substantially vertical axis.

It is a further object of the invention to 40 provide means permitting of the tilting of the supporting frame and a book carried thereby to various angular positions with respect to the horizontal so that the book may be presented at the best reading angle to suit 45 the convenience of the reader.

It is a further object of the invention to 50 form the supporting frame with relatively movable sections which are transversely adjustable in order to adapt the frame to books of different width to maintain the hinged wings of the supporting frame in positive engagement with the book sides or covers.

It is a still further object of the invention 55 to form the hinged wings with lever extensions which have their lower ends at posi-

tions below the hinged mountings for the wings, provided with rollers receivable within cam-slots provided in connection with relatively stationary parts of the frame structure, the said slots being of such design that 60 when the wings are positioned to close a book, the rollers will engage with portions of the slots to lock the wings against movement, whereby through the provision of the associated release mechanism, the said wings and 65 the crank extensions may be elevated to remove the rollers from the locking portions of the cam slots to permit of the oscillation of the wings and controlled movement thereof by the contact of the rollers with the walls 70 of said slots.

It is a still further object of the invention to provide a book holder of simple, efficient and economical construction which may be supported by a floor or table base and which 75 constitutes generally a marked improvement over mechanical book holders or supports of which I am aware.

With these and other objects in view, which will appear as the description proceeds, the 80 invention consists in the novel features of construction, combination of elements and arrangements of parts hereinafter fully described and pointed out in the appended claims.

In the accompanying drawings:

Fig. 1 is a side elevation of a book holder constructed in accordance with the present invention;

Fig. 2 is an end elevation of the book 90 holder;

Fig. 3 is a vertical transverse sectional view taken through the holder on the plane indicated by the line 3—3 of Fig. 1;

Fig. 4 is an end elevation of the holder disclosing the latter in an open position permitting of the reading of the pages of a book supported thereby;

Fig. 5 is a horizontal sectional view taken on the plane indicated by the line 5—5 of Fig. 2 and disclosing more particularly a bottom plan view of the adjustable book supporting frame;

Fig. 6 is a transverse sectional view taken 105 on the line 6—6 of Fig. 5;

Fig. 7 is a detail vertical sectional view of a means for tilting the supporting frame in a vertical plane;

Fig. 8 is a horizontal sectional view look- 110

ing downwardly on the under part of the supporting frame;

Fig. 9 is a detail sectional view on the line 9—9 of Fig. 8;

Fig. 10 is a vertical sectional view taken through the lower portion of the book holder disclosing the vertical axis about which the supporting frame may turn bodily in a horizontal plane and the tilting screw for adjusting the angularity of the holder and the book contained thereby.

Fig. 11 is a detail vertical sectional view taken on the line 11—11 of Fig. 3.

The specific form of my book holder, as illustrated in the accompanying drawings, comprises a metal base 1 which is of the type adapted to be received on a table, shelf, counter or other elevated horizontal supporting surface. It is obviously within the scope of my invention, however, to vary the length of the legs 2 of the base so that the latter may extend to the floor in order to produce a floor supported base if desired.

The base 2 terminates centrally and axially in a body 3 provided with a flat circular upper surface 4, constituting a bearing. Arranged for rotation on the surface 4 is a rotatable yoke 5, which yoke has its lower surface 6 shaped to conform to the base surface 4, whereby to provide a bearing contact permitting of the free rotation of the yoke about the vertical axis of the base. A headed pivot stud 7 passes through registering openings formed in the axial portions of the base and the yoke 5 in order to provide a positive vertical pivotal axis about which the yoke and the book supporting frame carried thereby may rotate. The bottom of the stud may be formed with locking nuts 8. It will be appreciated that suitable anti-friction bearings (not shown) may be positioned between the surfaces 4 and 6 if deemed advisable.

The yoke includes an up-turned arm 9 provided at its upper end with pivoted studs or trunnions 10, which trunnions are received within bearing openings provided in transversely extending frame members 11 and 12.

The arm 13 of the yoke 5, as shown in Fig. 7, carries pivot studs 14 which effect the pivotal support of a journal 15, in which there is rotatably mounted the smooth cylindrical shank portion of a tilting screw 16. The lower end of the screw 16, below the journal 15 is formed with manipulating wings 17 permitting the rotation of the screw, while the upper threaded shank portion of the screw is received within the threaded bore of a nut 18 which is pivotally carried by the trunnions 19 of the arms 11 and 12. It will be seen that by rotating the screw 16, the nut 18 will be caused to travel vertically thereof, thereby rocking the supporting frame structure of which the frame members 11 and 12 constitute a rigid part. By this means, the

frame structure and the book supported thereby may be oscillated about the pivotal connection afforded by the trunnions 10 to obtain the desired inclination or reading positions of the book 20 and this may be done by the simple adjusting of the tilting screw 16. Further, the frame structure as a whole may be rotated bodily about the vertical axis of the stud 7 to secure further adjustments in the desired reading positions of the book. The journal 15 and the nut 18 are supported by trunnions in order to compensate for the angularity of the screw 16 by reason of the swinging of the frame around the trunnions 10 and the connections between the lower end of said screw and the yoke 5.

The outer ends of the frame members 11 and 12 are, as shown in Fig. 8, secured to transversely extending end bars 21 by means of screws 22 or their equivalents so that the members 11 and 12 and the bars 21 will constitute a rigid frame assembly. Also, this rigid frame assembly comprises transversely spaced side bars 23. The side bars 23 have secured to their ends blocks 24, each of which having provided therein a cam-slot 25, which blocks are slidably carried by the bars 21 so as to move longitudinally of the bars 21.

To control the relative spacing of the side bars 23 in order to adapt the frame structure to books of different width, and to admit of the sliding of the blocks 24 on the bars 21, the side bars 23 are, as shown in Fig. 3, provided with horizontally extending screws 26 bearing right and left hand threads. The threaded shanks of the screws 26 are received within correspondingly threaded bores formed in a tubular member 27 which is confined for rotary movement about its longitudinal axis in connection with bearings 28 formed in conjunction with the frame members 11 and 12. Centrally the tubular member 27 is provided with an adjusting wheel 29 and it will be seen by manually rotating the wheel 29, rotary movement will be imparted to the tubular member 27. Since the latter is confined for rotation in the bearings 28, it follows that longitudinal movement either in outer or inward directions will be imparted to the screws 26, thereby varying the distance between the side bars 23.

The ends of the bars 23 are overlapped as at 30 to produce vertical guides for the reception of vertical legs 31 formed with longitudinally extending book back resting plates 32. These plates are movable to a limited degree vertically by the sliding movement of the legs 31 in the guides 30 but are restricted against longitudinal movement by the edges of the legs engaging with the corresponding edge surfaces of said guides.

Hinged as at 33 to the outer edges of the plates 32 are winged members 34 which are adapted to engage with the sides or covers of the book 20 and to provide rests for the

book when the latter is in the open position disclosed in Fig. 4 and to positively clamp and engage the sides in order to lock the book in a closed position as shown in Fig. 2. Secured to the wings or formed therewith are lever arms 35 which, as shown in Fig. 2, extend below the wing hinges 33. The extreme lower ends of the lever arms are provided with offset rollers 36 which are received within the slots 25 formed in the cam blocks 24.

Each of the slots 25 has its lower end provided with a locking pocket 37 in which the rollers 36 are positioned when the wings 15 are located to maintain a book in a closed condition. These pockets serve to prevent oscillation of the wings and the accidental opening of the book and therefore to permit of the release of said wings and their swinging 20 movement when desired, I provide in connection with each wing a release mechanism, which requires actual positive manual operation before the wings may be swung about their hinges. This release mechanism, 25 as shown more particularly in Fig. 3, consists in providing each of the wings with a finger plate 38 hinged as at 39 in connection with the outer edge of each wing. The finger plate engages with the upper end of 30 a spring-pressed pin 40 slidably carried in connection with bearings 41 carried by each of the wings. Each pin may be provided with a threaded collar 42 which cooperates with a spring 43 by means of which each pin 35 is held in a normally elevated position. The lower end of each pin normally rests on the outer portion of a detent 44 pivoted as at 45 in conjunction with the central portion of the side bars 23, while the inner part of 40 each detent is located immediately below the plates 32. By this construction, it will be seen that when it is desired to open the holder to permit of the viewing the pages of the book 20, the finger plates 38 are engaged 45 by the operator and rocked about their pivots 39. This results in moving the pins or stems 40 in a downward direction against the pressure of the springs 43, thereby rocking the 50 detents 44 and causing the same to elevate the plates 32, moving the legs 31 upwardly in the side bar guides 30. The upward movement of the plates 32 elevates the associated wings 34 and the lever arms 35, lifting the 55 rollers 36 out of the locking pockets 37. After this initial locking movement of the plates 38, the rollers 36 assume elevated positions in the slots 25 of the cam blocks which elevated positions do not interfere with the 60 hinged swinging movement of the wing members 34 in an outward direction. When the wing members are fully opened, as shown in Fig. 4, the rollers 36 reach the upper ends of the slots 25 so as to sustain the weight 65 of the book in an open stable position and

to receive the thrust pressures imparted thereby.

It will be noted that the weight of the book itself by being received by the plates 32 serves to retain the holder in a closed position and to positively lock the wings against separation by positively retaining the rollers 36 in the locking pockets of the cam slots. When the release mechanism has been operated by finger pressure to partly elevate the wings, 70 the weight of the book permits of the gradual separation and opening of the wings. In this manner, the weight of the book and forces of gravity are utilized to facilitate manipulation of the holder and to permit of the latter 75 to be easily and readily accomplished by persons of slight physical strength. Shouldered connecting strips 46 are carried by each of the plates 32 and slidably coact with each other to limit the extent of separation of the plates 32 when the wheel 29 is rotated to adjust the holder to books of different width. These strips force the side plates to act vertically together, that is, causing said plates to 80 maintain the same level and overcome binding of the opening and closing mechanism. 85

In view of the foregoing, it will be seen that the present invention provides a book holder of simple, sturdy mechanical construction which has the advantage of ease of operation 90 in the opening and closing of a contained book and also the further advantage of locking the book and the holder against accidental or undesired opening. As stated, to open the contained book, and to permit of the swinging movement of the clamping wings, it is first necessary to resort to an initial manual operation of a positive character, in this instance the actuation of the pivoted finger plates. Such manipulation releases the locking mechanism of the wings in order that the latter may be gradually extended to assume a fully opened position. In these operations, the lever arms, the rollers 36 and the slotted cam blocks 24 serve an important part, since 95 the pockets in the ends of the slots function in cooperation with the lever arms to normally lock the wings against movement and, when released from the pockets, the lever arms and the rollers travel in the slots to provide for the controlled opening or descent of the means, and, when the rollers reach the upper ends of the slots, to check such opening and provide a strong construction for receiving the weight and thrust imposed on the 100 wings by said book. Further, the construction of the holder is such as to permit the book containing frame to revolve about both vertical and horizontal axis to assume proper or convenient positions best suited for the 105 requirements of the reader. Again, the supporting frame is readily adjustable transversely of itself so that the wings may be adapted to books possessing considerable 110 variation in width. The holder may be 115

placed on a table or other form of horizontal support or may be provided with a conventional type of floor stand. The holder prevents deposits of dust between book pages and 5 retains the pages against in-rolling or folding of its leaves.

While I have described in detail the preferred form of my present invention, yet it will be apparent that variations and modifications 10 may be made therein without departing from the scope of the invention as the latter has been defined in the following claims.

What is claimed is:

1. A book holder comprising a supporting 15 base formed with a hub, a yoke rotatably mounted on said hub for turning movement about a substantially vertically disposed axis, a frame having at one side a horizontal pivotal connection with said yoke, threaded adjusting means pivotally connected with said yoke and the other side of said frame and serving to retain said frame in various positions of angular adjustment with respect to said base, wing members having hinged connections 25 with said frame, and threaded adjusting means cooperative with said frame and said wing members for varying the spacing of said wing members.

2. In a book holder, a supporting base provided with a central hub, a member rotatably 30 mounted on said hub for turning movement about a substantially vertically disposed axis, a frame arranged over said member, a substantially horizontally disposed pivotal connection between one side of said frame and said member, pivotally movable threaded means cooperative with the other side of said frame and said member for varying and maintaining the operating positions of said 40 frame with respect to said base by moving the frame about said horizontal pivotal connection, and means carried by said frame for supporting a book.

3. In a book holder, a supporting base provided with a central hub, a member rotatably 45 mounted on said hub for turning movement about a substantially vertically disposed axis, a frame arranged over said member, a substantially horizontally disposed pivotal connection between one side of said frame and said member, pivotally movable threaded means cooperative with the other side of said frame and said member for varying and maintaining the operating positions of said 50 frame with respect to said base by moving the frame about said horizontal pivotal connection, and adjustable means carried by said frame for supporting books of varying thickness.

60 4. In a book holder, a supporting base provided with a central bearing portion, a member supported by said base cooperative with said bearing portion for turning movement about a substantially vertically disposed axis, 65 a superposed frame, a horizontal pivotal con-

nnection between said frame and said rotatable member, a threaded nut pivotally carried by said frame, a bearing pivotally carried by said member, a manually operated screw having its threaded shank portion received within said nut and rotatably mounted in said bearing, whereby upon the rotation of said screw, said frame may be adjusted for swinging movement about said horizontal pivotal connection, and adjustable book engaging members supported by and arranged above said frame.

5. In a book holder, a supporting base, a frame carried by said base, a compound pivotal mounting for said frame permitting of the adjustment thereof about both vertical and horizontal axes, means for retaining said frame in its positions of adjustment about said axes, spaced book back supports carried by said frame, means mounted in conjunction with said frame for controlling the spacing of said supports, hinged wings connected with the outer longitudinal edges of said supports, and means for locking said means in positions of book closure.

6. In a book holder, a supporting base, a frame carried by said base, a compound pivotal mounting for said frame permitting of the adjustment thereof about both vertical and horizontal axes, means for retaining said frame in its positions of adjustment about said axes, spaced book back supports carried by said frame, means mounted in conjunction with said frame for controlling the spacing of said supports, hinged wings connected with the outer longitudinal edges of said supports, and means for limiting the extent of relative separation of said supports.

7. In a book holder, a book supporting frame, a base, compound pivotal connections between said base and said frame permitting of adjustment of the frame about horizontal and vertical axes, a pair of book resting plates carried by said frame and slidably toward and from each other, screw mechanism carried by said frame for regulating sliding movement between said plates, a pair of hinged wings carried by said plates, means for locking said wings in positions of book closure, and release mechanism carried by 115 said wings and manually operable to release the locking mechanism to permit of the swinging of said wings to positions providing for the opening of a book received therebetween.

8. In a book holder, a base, a frame mounted on said base and pivotally adjustable about horizontal and vertical axes, side bars extending parallel to said frame and slidably connected therewith for adjustment transversely of the frame, threaded adjusting means carried by said frame and connected with said side bars for controlling the sliding movement thereof on said frame, spaced longitudinally extending book rest plates connected with said bars, hinged wings connected 125

to the outer edges of said plates, blocks connected with said side bars and provided with cam shaped slots, and lever arms formed with said wings and having the lower portions 5 thereof arranged to project below the hinged mountings for said wings, the lower portions of said arms being receivable within the slots provided in said blocks.

9. In a book holder, a base, a frame, coming 10 pound pivotal connections between said frame and said base permitting of the adjustment of said frame about both vertical and horizontal axes, book supports transversely adjustable on said frame, hinged wings connected with said book supports, blocks connected with said book supports provided with cam shaped guides, and crank extensions formed with said wings and projecting below the hinged mountings of the latter to cooperate 15 with the guides provided in connection with said blocks.

10. In a book holder, a base, a frame pivotally adjustable on said base for turning movement about both vertical and horizontal 20 axes, book supports slidably carried by said frame, manually adjustable means for varying the spacing of said book supports to adapt said supports to books of different thickness, cam shaped guides rigidly formed with said 25 book supports, wings hinged to the outer edges of said book supports, lever extensions formed with said wings and having their lower portions arranged to be received within said cam guides, said guides being formed 30 to lock said wings against swinging movement when in positions of book closure, and manually operated release devices carried by said wings and operable to move said lever 35 extensions from the locking positions of said guides to permit of the swinging of said wings to positions providing for the opening 40 of a book received therebetween.

11. In a book holder, an under structure, book supports carried by said structure, book 45 back resting plates mounted for vertical movement on said supports, cam guides having pockets in their lower ends, wings hinged to the outer edges of said plates, lever extensions formed with said wings and having 50 their lower portions arranged to be received within said cam guides, the pockets formed in said guides serving to lock said wings in positions of book closure, pivoted detents arranged between said supports and plates, and manually operated release devices including 55 spring pressed stems for rocking said detents to raise said plates and elevate said wings from their engagement with the pockets formed in said cam guides.

60 12. In a book holder, an under structure, book supports carried by said structure, book back resting members mounted for vertical movement of said supports, hinged wings connected to the outer edges of said mem-

bers for movement therewith, substantially horizontally arranged cam guides formed with said supports having upwardly and downwardly directed end portions formed therewith, and extensions provided upon the lower portions of said wings and projecting below the hinged mounting of the latter to cooperate with said guides, the vertically movable 70 mountings of said book back resting members permitting said wing extensions to follow said guides throughout the curvatures thereof.

13. In a book holder, a base, book supports carried by said base, book back resting members mounted for vertical movement on said supports, hinged wings connected to the outer edges of said members for movement therewith, substantially horizontally arranged cam guides formed with said supports having upwardly and downwardly directed end portions formed therewith, and extensions provided upon the lower portions of said wings and projecting below the hinged mountings of the latter to cooperate with said guides, the vertically movable 80 mountings of said book back resting members permitting engagement between said wing extensions and guides throughout the lengths of the latter and effects the positive 85 positioning of said wings in either their raised or lowered position.

14. In a book holder, a base, book supports carried in connection with said base, book back resting plates mounted for vertical movement on said supports, wings hingedly 90 connected to the outer edges of said plates, substantially S-shaped cam guides formed with said supports, and lever extensions provided upon the lower portions of said wings for engagement with said cam guides to effect the vertical movement of said plates 95 and wings during the opening and closing action of said wings.

15. In a book holder, a base, book supports carried in connection with said base, wings hingedly united to said support, substantially 100 S-shaped guides formed with said supports, and crank extensions formed with said wings and projecting below the hinged mountings of the latter to cooperate with said guides in holding the wings in their 105 book opening or closing position.

16. In a book holder, a base, a frame supported by said base, book supports on said frame, hinged wings connected with said supports, substantially S-shaped guides formed in connection with said supports, and extensions formed with the lower portions of said wings and projecting below the hinged mountings of the latter to cooperate 120 with said guides.

In testimony whereof I affix my signature.

FREDERICK C. LANDSITTEL.
